Patented Apr. 8, 1975

234,830

CARRIER FOR TENNIS EQUIPMENT OR THE LIKE

Irvin Udell, 2200 Benjamin Franklin Parkway,
Philadelphia, Pa. 19130

Filed Nov. 13, 1972, Ser. No. 305,999

Term of patent 3½ years

Int. Cl. D3—01

U.S. Cl. D87—1 R

FIG. 2.

FIG. 3.

FIG. 1.

FIG. 4.

FIG. 5.

FIG. 6.

FIG. 1 is a front elevational view of a carrier for tennis equipment or the like embodying my new design, shown in open position;

FIG. 2 is a top plan view;

FIG. 3 is an elevational view looking from the left of FIG. 1;

FIG. 4 is an elevational view looking from the right of FIG. 1;

FIG. 5 is a rear elevational view; and

FIG. 6 is a perspective view in closed position.

I claim:

The ornamental design for a carrier for tennis equipment or the like, as shown.
